CARBURETOR IMPROVEMENT

Edgar R. Schneider, St. Louis, Mo., assignor to
 Carter Carburetor Corporation, St. Louis, Mo.,
 a corporation of Delaware

Application June 23, 1943, Serial No. 492,191

4 Claims. (Cl. 287—53)

This invention relates to carburetors for internal combustion engines and more particularly concerns carburetor throttle operating levers used in connection therewith.

It is the primary object of the present invention to provide an inexpensive, conveniently detachable throttle operating lever.

Other objects and advantages will appear upon reference to the following description and accompanying drawing referring to which:

Fig. 1 is a side elevation of a modern carburetor incorporating a form of the present invention.

Fig. 2 is a fragmentary portion of the carburetor shown in Fig. 1 taken on line 2—2 of Fig. 1.

Fig. 3 is an enlarged view of a portion of the operating lever.

Numeral 1 generally indicates a modern carburetor having a mixture conduit 2. The outlet of the mixture conduit is controlled by a butterfly-type throttle valve 3 which is rigidly mounted on a rotatable shaft 4. The shaft 4 is journaled at its ends in the walls of the mixture conduit at 5 and 6 and projects substantially through one wall as indicated at 7. The projecting end of shaft 4 is milled flat for some distance from its end as indicated at 8.

A throttle operating lever is generally indicated at 9. The lever 9 is provided with a D-shaped perforation 10 adapted to receive in slip-fit relationship the flattened projecting end of shaft 4. Lever 9 is further provided with an arm perforated near its outer end at 11 to receive an operating rod (not shown) and an arm 12 which carries in threaded engagement an adjustable stop screw 13. Cast integral with the carburetor body is an abutment 14 which is engaged by the stop screw 13 to limit the closing movement of the throttle valve. Lever 9 is also provided with a projection 15 which engages the abutment 14 to provide a wide open throttle valve stop.

It will be understood that to permit economical manufacture, dimensional tolerances will be necessary to insure the interchangeable slip-fit assembly of the lever on the shaft. It will also be seen, however, that any looseness of the lever on the shaft due to this necessary tolerance will be multiplied at the edge of the butterfly throttle valve and as this would seriously affect the selected idling speed, it must be prevented. To overcome this difficulty, I have provided a coiled spring 16 having its inner end attached to shaft 4 by passing through a perforation 17 therein and having its outer end bearing against the lever

at 18. The outer end of the spring 16 is coiled as indicated at 19 and circling the projecting end of stop screw 13. It will be seen with this arrangement that any lost motion between the shaft 4 and lever 9 will be taken up as shown in a somewhat exaggerated condition in Fig. 3 by the spring 16 and that the lever 9 is keyed by the inner end of the spring which passes through the shaft preventing the longitudinal movement 10 on the shaft.

The foregoing description and accompanying drawing are intended to be illustrative and not limiting and the exclusive use of all modifications within the scope of the appended claims is contemplated.

I claim:

1. The combination of a rotatable valve shaft having a non-circular end portion, an operating lever having a perforation substantially similar in shape to said non-circular shaft end and of such size as to receive said shaft end for limited rotation relative thereto, and resilient means for urging said lever in a rotational direction with respect to said shaft whereby any lost motion due to the free fit of the lever on the shaft is resiliently taken up.

2. The combination of a rotatable valve shaft and an operating lever, said shaft having a non-circular end portion of reduced section providing a shoulder spaced from the end thereof, said lever having a perforation substantially similar in shape to said non-circular shaft end and of such dimensions as to permit the free slip-fit assembly of the lever on the shaft, said shaft being further characterized by a cross bore near the outer end of the reduced portion, and a coiled spring having one end passing through said cross bore and its other end bearing against said lever whereby said lever is urged in a rotational direction with respect to said shaft and restrained longitudinally by said shoulder and the inner end of said spring.

3. In combination, a rotatable valve shaft, an operating lever mounted on said shaft and capable of limited rotation relative thereto, and resilient means normally urging said lever into one of its extreme positions relative to said shaft.

4. In combination, a rotatable shaft, an operating lever mounted thereon and capable of limited lost motion relative thereto, and a torsion spring stressed between said shaft and lever and normally maintaining said lever in one of its extreme positions relative to said shaft.
